UNITED STATES PATENT OFFICE.

CHARLES J. MAYER, OF PHILADELPHIA, PENNSYLVANIA.

DESIGN FOR A RAIL-BOND.

SPECIFICATION forming part of Design No. 32,019, dated December 19, 1899.

Application filed November 15, 1899. Serial No. 737,136. Term of patent 14 years.

To all whom it may concern:

Be it known that I, CHARLES J. MAYER, a citizen of the United States, residing at the city of Philadelphia, in the county of Philadelphia and State of Pennsylvania, have invented and produced a new, useful, and original Design for a Rail-Bond, of which the following is a specification, reference being had to the accompanying drawings, forming part ⁵ hereof, in which—

Figure 1 is a top or plan view of a rail-bond of the design of my invention, and Fig. 2 is a side view of the same.

The leading feature of my design consists ¹⁵ of the particular shape or configuration and arrangement of the bond.

Referring to the drawings, *a* and *a'* represent the end block-like devices curved at *a²* and *a³* and provided with flaring lips *a⁴* and ²⁰ *a⁵* and with transverse projections *b* and *b'*.

c and *c'* are nested metal strips connected with the ends *a* and *a'*, and respectively provided with bends or offsets *d* and *d'*, whereof the bend or offset *d* is substantially **U** shape

and the bend or offset *d'* is substantially **V** ²⁵ shape, and both offsets or bends located nearer to one end block than to the other and with irregular-shaped openings *e* and *e'* formed therein within the longitudinal outline of the nested metal strips, the offsets or bends being ³⁰ confined within the longitudinal plane of said strips and the latter where joined to the blocks *a* and *a'* being disposed and extending beyond the plane of said blocks, as clearly illustrated in Fig. 1 of the drawings. ³⁵

Having thus described my invention, what I claim as new, and desire to secure by Letters Patent, is—

The design for a rail-bond, herein shown and described. ⁴⁰

In witness whereof I have hereunto set my signature, this 14th day of November, A. D. 1899, in the presence of two subscribing witnesses.

CHARLES J. MAYER.

Witnesses:

J. WALTER DOUGLASS,
THOMAS M. SMITH.
